CASSEROLE COVER OR THE LIKE

Gregory Mirow, Corning, N.Y., assignor to Corning
Glass Works, Corning, N.Y.

Filed June 14, 1971, Ser. No. 153,158

Term of patent 14 years

Int. Cl. D7—01

U.S. Cl. D44—15 A

Fig. 1

Fig. 2

Fig. 3

FIG. 1 is a top plan view of a casserole cover or the like showing my new design.

FIG. 2 is a front elevational view.

FIG. 3 is a side elevational view.

The characteristic feature of the design resides in the specific ornamentation applied to the top surface of the casserole cover.

I claim:

The ornamental design for a casserole cover or the like, as shown and described.
